UNITED STATES PATENT OFFICE.

JOHN F. BERRY, OF BANGOR, MAINE.

MOLD.

Application filed June 18, 1928. Serial No. 286,183.

This invention relates to a mold for manufacturing concrete blocks for use in building chimneys, posts and piers, etc., and has for its object to provide, in a manner as hereinafter set forth, a mold for expeditiously molding hollow concrete blocks with or without a flue opening.

Another object of the invention is to provide, in a manner as hereinafter set forth, a mold for expeditiously molding hollow four walled concrete blocks with or without a flue opening and with the outer periphery of the block simulating superposed courses of brick.

A further object of the invention is to provide, in a manner as hereinafter set forth, a mold for the purpose referred to so constructed and arranged to prevent the entrance of water or creosote or foreign substances into the molding cavity of the mold from the outside or from the inside of the latter.

A further object of the invention is to provide, in a manner as hereinafter set forth, a mold for the purpose referred to so constructed and arranged for expeditiously molding hollow concrete blocks formed in a manner to interlock with each other when arranged in superposed relation and further having the outer periphery thereof simulating superposed courses of brick.

Further objects of the invention are to provide, in a manner as hereinafter set forth, a mold for manufacturing hollow concrete blocks which is simple in its construction and arrangement, strong, durable, thoroughly efficient in its use, readily assembled, conveniently handled and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation of a mold in accordance with this invention and with the elements of the mold assembled.

Figure 2 is a top plan view of a mold in accordance with this invention and with the elements of the mold assembled.

Figure 3 is a section on line 3—3 Figure 2.

Figure 4 is a sectional plan on line 4—4 Figure 3.

Figure 5 is a vertical sectional view of a modified form of mold.

Figure 6 is a section on line 6—6 Figure 5.

Figure 7 is a fragmentary view in vertical section illustrating a filler member positioned in the bottom of the molding cavity to provide flat bottom blocks.

Figure 8 is a sectional elevation of the filler member.

Figure 9 is a fragmentary view in elevation illustrating the block formed with a flue opening.

Figure 10 is a fragmentary view in elevation of the block provided with a flat bottom.

Figure 11 is a view similar to Figure 9 of the block having the walls thereof imperforate.

Referring to Figures 1, 2, 3 and 4 of the drawings the body portion of the mold is indicated generally at 1, is of square contour in plan and has the walls thereof indicated at

2, 3, 4 and 5 disposed upon an outward inclination from the bottom to the top thereof and said body portion 1 at its upper end is formed with a laterally extending, right angularly disposed, continuous flange 5.

Formed integral with the inner face of the walls of the body portion 1, a substantial distance above the lower end thereof is a bottom piece or bottom referred to generally at 6 and in cross section formed of a flat outer part 7,

an upwardly extending, curved intermediate part 8 and a depending curved inner part 9 which is reversely curved with respect to the part 8. The arc of the part 8 is less than the arc of the part 9 and the latter merges into

a hollow, upstanding, core 10 of less height than the height of the body portion 1 and which is formed with a closed, flat top 11

having a centrally disposed depending boss 12 and further having a centrally disposed opening 13 which is continued through the boss 1 and has the wall thereof threaded.

The core 10 is tapered and of square outline. The body portion is open at its top.

Arranged within the body portion of the block 1 are four, vertically disposed wall members indicated at 14, 15, 16 and 17 of like construction. The wall members extend

above the top of the body portion 1 and are formed at their upper ends with outwardly extending, right angularly disposed flanges

18. The inner face of each wall member has

formed integral therewith a series of superposed, spaced transversely extending beads 19 and spaced, vertical beads 19' of rounded contour. The outer face of each wall member 5 is formed with a plurality of spaced, parallel, vertically disposed webs 20 which gradually increase in width from their lower to their upper ends and the upper ends of the webs are integral with the lower faces of the 10 flanges 18. The side edges of the wall members are beveled, as at 21 whereby a mitre joint is provided when the wall members are mounted in position. The wall members are seated on the flat outer part 7 of the bottom 15 6 and the webs 20 engage the inner face of the body portion 1 for the purpose of maintaining the wall members perpendicular.

Mounted upon the inner part 9 of the bottom 6 and opposing the core 10, as well as 20 extending thereabove, but of less height than the wall members 14 to 17, is a series of wall members 22, 23, 24 and 25. That face of the wall members 22 to 25, which opposes the rear faces of the wall members 14 to 17 respectively 25 is plane and the other face of the wall members 22 to 25 has laterally extending, vertically disposed parallel spaced webs 26 which gradually increase in width from the lower to the upper ends thereof and bear 30 against the core 10 for the purpose of maintaining the wall members 22 to 25 in a perpendicular position.

The wall members 14 to 17 are termed the outer wall members and the wall members 35 22 to 25 are termed the inner wall members and said outer and inner wall members coact with the bottom 6 to provide a molding cavity 27 of a height greater than the core 10. The inner wall members have their side edges 40 beveled as at 28 to provide a mitre joint therebetween.

The upper end of the molding cavity 27 is closed by a head member 29 in the form of a frame and in cross section is of a contour 45 substantially the same as the cross sectional contour of the bottom 6. The head piece 29 is formed with spaced vertical flanges 30, 31 and with the flange 30 bearing against the inner face of the outer wall members and 50 flush with the tops of these latter. The flange 31 bears against the non-webbed face of the inner wall members and is flush with the tops thereof. The flange 31 is arranged below the flange 30. The head piece 29 has 55 vent openings 32. The head piece 29 provides the top wall of the molding cavity, the bottom 6 of the body portion 1 provides the bottom of the molding cavity, the wall members 14 to 17 form the outer wall of the molding cavity and the wall members 22 to 25 provide the inner wall of the molding cavity.

Associated with the wall members 22 to 60 27, as well as being adjustably connected to the top of the core 10 is a retainer member 65 for the wall members 22 to 27 and for the

head piece 29. The retainer member is indicated at 32 and includes a depressed part formed with a boss 33 on its upper face. The boss is located centrally of the member 32 and the latter is formed with an opening 34 extending therethrough and also through the boss. The non-depressed part 35 of the retainer member 32 seats on the top edges of the wall forming members 22 to 27 and on the flange 31 of the head piece 29.

Secured to the top 11 of the core 10 and extending through the opening 34 in the retainer member 32 is a threaded stem 36 carrying a wheel 37 which revolves relative to said stem 36 and engages the boss 33 for the purpose of clamping the retainer member 32 in the position as shown in Figure 3 and which will retain the head piece 29 in position. The head piece 29 acts as a means for bracing the wall members 14 to 17 relative to the wall members 22 to 27.

When the mold is employed the retainer member 32 is positioned and after the cement has been supplied to the molding cavity 27, the retainer member 32 is removed and head piece 29 mounted in position at the upper end of the molding cavity and upon the cement. The retainer member 32 is then arranged in position and retains the head piece 29 at the top of the molding cavity until the block 95 dries.

The body portion 1 is provided with a pair of trunnions 38 so that it can be turned to dump the molded block therefrom, after the retainer member 32 and head piece 29 have 100 been removed therefrom. The head piece 29 carries a pair of handles 39 to facilitate the removal and positioning of the same with respect to the top of the molding cavity 27.

The shape of the bottom 6 and head piece 29 provides on the molded block 40 a rounded 105 continuous rib 41 at its top edge and a continuous concavity 42 at its bottom edge whereby when the blocks 40 are arranged in superposed relation they will interlock or interengage with each other.

If it be desired to provide the bottom of the block flat, a filler member 43 is employed and which is positioned at the bottom of the molding cavity 27. See Figure 7.

To provide one of the walls of the block with a flue opening the wall forming members 15 and 26 are removed and wall forming members 44, 45 are substituted therefor and in this connection see Figures 5 and 6 which illustrate a mold for manufacturing concrete blocks of the form shown in Figure 9 and indicated at 46. The flue opening formed in one of the walls of the block 46 is indicated at 47. In the modified form of 120 mold shown in Figures 5 and 6 the core 48 which is integral with the bottom 49 of the body portion 50 is formed slightly different from the core 10 and in this connection one side of the core 48, said side indicated at 49, 130

has an inset upper part 50' which provides a shoulder 51. See Figure 5. Otherwise than that as stated the core 48 is constructed similarly to the core 10. The wall forming member 44 is formed with an inwardly extending portion 47' of annular form and closed as at 50" at its inner end. The wall forming member 45 is provided with an outwardly extending annular part 51' closed at 10 its outer end as at 52. The parts 47' and 51' oppose each other, as well as abut each other when the wall forming members 44 and 45 are arranged in position. See Figure 5. The wall forming member 44 has outwardly 15 extending lugs 53 which abuts the body portion 50. The wall forming member 45 has lateral lugs 54 which abut the part 50' and shoulder 51 of the side 49 of the core 48. The parts 47' and 51' are surrounded by a sleeve 20 or thimble 55 having its outer end formed with an outwardly extending lateral flange 56. The sleeve 55 extends from the wall forming member 44 to the wall forming member 45. See Figure 5. Otherwise than that 25 as stated the construction of the mold shown in Figure 5 is the same as that shown in Figures 1 to 4 and the parts of the mold shown in Figures 5 and 6 which correspond to the parts shown in Figures 3 and 4 are provided 30 with reference characters corresponding to those employed in Figures 3 and 4.

The brick shown in Figure 10 is indicated at 57 and has a flat bottom 58.

The construction of the mold as illustrated 35 and described provides for expeditiously molding hollow, four walled concrete blocks with or without a flue opening and with the outer faces of the walls of the block simulating superposed courses of bricks and such simulation is provided by the beads 19, 19'. Owing to the manner of setting up the core with respect to the bottom of the body portion and further owing to the manner of sealing the molding cavity water or creosote 40 is prevented from entering the molding cavity from outside of the body portion or from within the core.

It is thought the many advantages of a 45 mold for the purpose set forth and in accordance with this invention, can be readily understood, and although the preferred embodiment of the invention is as illustrated and described, yet it is to be understood that changes in the details of construction can be had which fall within the scope of the invention as claimed.

What I claim is:

1. A mold comprising an open top body portion including a bottom piece terminating 50 in a hollow closed top core surrounded and spaced from the walls of the body portion, an inner and an outer set of wall forming members, said sets arranged in spaced relation seating on and forming in connection with 55 said bottom piece an open top molding cavity, a head piece positioned between said sets, bracing these latter and forming a closure for the top of the molding cavity, and a retaining member detachably connected with the top of said core and seating on said head piece and the top edges of the inner set of wall forming members.

2. A mold comprising an open top body portion including a bottom piece terminating in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, bracing these latter and forming a closure for the top of the molding cavity, and a retaining member detachably connected with the top of said core and seating on said head piece and the top edges of the inner set of wall forming members.

3. A mold comprising an open top body portion including a bottom piece terminating in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, bracing these latter and forming a closure for the top of the molding cavity, and a retaining member detachably connected with the top of said core and seating on said head piece and the top edges of the inner set of wall forming members, the wall forming members of said outer set having their inner faces provided with spaced ribs.

3. A mold comprising an open top body portion including a bottom piece terminating in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, bracing these latter and forming a closure for the top of the molding cavity, and a retaining member detachably connected with the top of said core and seating on said head piece and the top edges of the inner set of wall forming members, said body portion being tapered, and said wall forming members having means seating against said core and inner face of said body portion for maintaining said members perpendicular.

4. A mold comprising an open top body portion including a bottom piece terminating in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, bracing these latter and forming a closure for the top of the molding cavity, and a retaining member detachably connected with the top of said core and seating on said head piece and the top edges of the inner set of wall forming members, one of the wall forming members of each set having an offset portion, said offset portions extending towards each other and across the molding cavity, and a tubular member surrounding said offset portions and abutting the wall forming members provided with such portions.

5. A mold comprising an open top body portion including a bottom piece terminating in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, 10 bracing these latter and forming a closure for the top of the molding cavity, and a retaining member detachably connected with the top of said core and seating on said head piece and the top edges of the inner set of wall forming members, said bottom piece and said head piece in cross section being reversely curved and of like curvature.

6. A mold comprising an open top body portion including a bottom piece terminating 20 in a hollow closed top core surrounded and spaced from the walls of the body portion, an inner and an outer set of wall forming members, said sets arranged in spaced relation, seating on and forming in connection with said bottom piece an open top molding cavity, a head piece positioned between said sets, 25 bracing these latter and forming a closure for the top of the molding cavity, and a retaining member detachably connected with the top of said core and seating on said head piece and the top edges of the inner set of wall forming members, said head piece provided with openings and of reverse curvature in 30 transverse section, said bottom piece being of reverse curvature in transverse section and the curvature of the bottom piece conforming substantially to the curvature of the head piece.

7. A mold comprising a tapered open top body portion having a bottom piece terminating in an upstanding hollow, closed top, tapered core, opposed, spaced sets of wall forming members seating in said bottom piece and extending above the core and forming in connection with said bottom piece an open top molding cavity, means carried by 40 said members and bearing against the core and body portion for maintaining the members perpendicular, a removable closure for the top of said molding cavity bearing against the members of said sets, and retaining means 45 adjustably connected with the top of the core, arranged over the latter and seating on said closure and on the top of the inner set of wall forming members.

8. A mold comprising a tapered open top body portion having a bottom piece terminating in an upstanding hollow, closed top, tapered core, opposed, spaced sets of wall 50 forming members seating in said bottom piece and extending above the core and form-

ing in connection with said bottom piece an open top molding cavity, means carried by 55 said members and bearing against the core and body portion for maintaining the members perpendicular, a removable closure for the top of said molding cavity bearing against the members of said sets, and retaining means adjustably connected with the top of the core, arranged over the latter and seating on 60 said closure and on the top of the inner set of wall forming members, said closure and bottom piece being reversely and correspondingly curved.

9. A mold comprising a tapered open top 75 body portion having a bottom piece terminating in an upstanding hollow, closed top, tapered core, opposed, spaced sets of wall forming members seating in said bottom piece and extending above the core and forming in 80 connection with said bottom piece an open top molding cavity, means carried by said members and bearing against the core and body portion for maintaining the members perpendicular, a removable closure for the top of said molding cavity bearing against the members of said sets, retaining means 85 adjustably connected with the top of the core, arranged over the latter and seating on said closure and on the top of the inner set of wall forming members, one of the wall forming members of each set having an offset extending into the molding cavity, said offsets coacting to bridge the cavity, and a sleeve enclosing 90 said offsets and abutting the wall forming members having the offsets.

10. A mold comprising a tapered open top body portion having a bottom piece terminating in an upstanding hollow, closed top, tapered core, opposed, spaced sets of wall forming members seating in said bottom piece and extending above the core and forming in connection with said bottom piece an open top molding cavity, means carried by said members and bearing against the core and body portion for maintaining the members perpendicular, a removable closure for the top of said molding cavity bearing against the members of said sets, retaining means 100 adjustably connected with the top of the core, arranged over the latter and seating on said closure and on the top of the inner set of wall forming members, one of the wall forming members of each set having an offset extending into the molding cavity, said offsets coacting to bridge the cavity, and a sleeve enclosing 105 said offsets and abutting the wall forming members having the offsets.

In testimony whereof, I affix my signature 110 hereto.

JOHN F. BERRY.
